 tion of Illinois

Application July 31, 1946, Serial No. 687,460

5 Claims. (Cl. 15—87)

1

This invention relates to improvements in power driven street sweeping brooms and more particularly this invention relates to improvements in brooms adapted to operate at the side of a sweeping machine for sweeping out the gutters and in the means of driving such side brooms.

In street sweeping machines it is customary to employ an auxiliary side broom to sweep out the gutters. This is chiefly due to the fact that the 10 gutters are usually inclined at an angle to the adjacent surface of the street. The main broom which sweeps the street surface is not adapted to dig into the gutter and remove dirt and debris. Therefore a side broom the working surface of which may be inclined to correspond to the angle of the gutter is employed for this purpose.

It is therefore an object of this invention to provide a power driven broom which may be quickly and accurately adjusted for sweeping various shapes of gutters.

It is another object of this invention to provide improved means for lifting the side broom out of contact with the street when it is not sweeping.

It is a further object of this invention to provide improved means for driving a side broom.

It is a still further object of this invention to provide drive means for a side broom wherein the side broom drive may be disconnected from the main drive when it is desired to move the vehicle without operating the side broom as for instance when going to and from the scene of operations.

Another important object of this invention is to provide a side broom assembly which may be dismounted as a unit from the sweeping machine thereby permitting adjustment and alignment of all moving parts prior to installation.

Another and still further object of this invention is to provide a drive means for a side broom in which the mechanism is simple in construction, protected from dirt and dust and is readily accessible for maintenance work.

A further object of this invention is to provide improved means of adjusting the operating height of side brooms to compensate for wear on the bristles.

Another object of this invention is to provide an enclosing housing about the driving mechanism which will maintain its dirt resisting seal no matter at what angle the broom is adjusted.

According to the general features of the invention a side broom, adapted to be placed in contact with a surface to be swept, is mounted for rotation about a substantially vertical shaft which

is driven through bevel gears from the main power transmission mechanism of the sweeping machine.

A feature of this invention is the provision of 5 a V-shaped member which is attached at its apex to a lift-yoke about the lower portion of the broom assembly and which is adjustably secured near the end of each arm to a rigid frame member, whereby the side broom drive shaft may be selectively adjusted in directions both laterally and rearwardly of the machine.

Another feature of this invention is the provision of a bellcrank assembly pivoted on a frame member, and connected at one end to a remotely controlled hydraulically actuated cylinder by means of which the broom may be lifted off the ground when not in use.

In accordance with another feature of the invention there is provided a completely enclosed drive mechanism into which is incorporated a slide clutch for disconnecting the side broom drive mechanism from the main drive of the sweeping machine when it is desired to operate the machine without operating the broom.

Other objects, features and advantages of the present invention will be readily apparent to those skilled in the art from the detailed description of the annexed sheets of drawings.

On the drawings:

Figure 1 is a more or less side elevational view of a street sweeping machine embodying the features of the present invention.

Figure 2 is a fragmentary front view partially in section and partially broken away, of the side broom assembly and the broom drive mechanism and mounting therefor.

Figure 3 is a fragmentary plan view, partially in section of the structural framework at the front end of the vehicle showing the method of 40 supporting the side broom adjusting bars and the hydraulically operated lift cylinder.

Figure 4 is a fragmentary front elevational view, partially in section and partly broken away, taken substantially on line IV—IV of Figure 1 looking in the direction indicated by the arrows.

Figure 5 is a sectional view taken on line V—V of Figure 2 looking in the direction indicated by the arrows.

Figure 6 is a fragmentary sectional view taken on line VI—VI of Figure 3 looking in the direction indicated by the arrows.

Figure 7 is a fragmentary sectional view taken on line VII—VII of Figure 3 looking in the direction indicated by the arrows.

Figure 8 is a fragmentary sectional view taken

on line VIII—VIII of Figure 3 looking in the direction indicated by the arrows.

Figure 9 is a fragmentary sectional view taken on line IX—IX of Figure 4.

A side broom assembly and drive embodying the features of the present invention is especially adapted for use on a self-propelling small size or "baby" street sweeping machine, on the order of that disclosed in my copending application Serial No. 646,525 filed February 9, 1946 and which issued April 25, 1950 as U. S. Patent No. 2,505,199.

Such a sweeping machine may comprise a front or engine section 10 and a rear or sweeping section 11 with a cooperatively intervening operator's cab 12. Supporting the front power section 10 is a framework or chassis comprising structural member 13 which may also support the operator's cab and afford a structural connection with the rear sweeping section 11 of the machine. Mobility of the machine is afforded by a pair of rear driving wheels 14 supporting the sweeping section 11 and driven in a suitable manner as by means of a chain and sprocket drive 15 from a power transmission system 16 which is preferably located in the operator's cab 12. The front of the machine is supported by a steerable wheel 17 which is mounted under the chassis 13.

The sweeping section 11 is preferably constructed principally from sheet metal, including side plates 18 secured to a top plate (not shown) to form a substantially inverted U-shaped housing. This housing may be supported by fastenings at its forward end to the structural members 13 and to the transmission housing. At its rearward end the housing may be supported by suitable bearing sleeves secured to the rear axle 19. A splash guard and closure plate structure 20 at each side of the sweeping section 11 encloses the drive wheels and the operating mechanism of the machine.

Mounted for operation partially between the forward portions of the rear wheels 14 on an axis parallel to rear axle 19 and accessible through appropriate removable sections (not shown) of the outer closure plate structure 20 and openings in the inner side plate 18 is a main sweep broom 22 of the rotary cylindrical type. The broom 22 may embody any preferred construction and comprises radial bristles, mounted about a suitable core supported by an axle shaft 23. Shaft 23 may be mounted in a suitable fashion parallel to the axle 19 upon the rear ends of supporting arms 24 pivotally connected at their forward ends adjacent the bottom of cab 12. Main sweeping broom 22 may be driven through a chain and sprocket drive 25 from the power transmission 16. For a more detailed description of the construction and operation of the main broom assembly reference may be had to my copending application Serial No. 667,070, filed May 3, 1946.

Disposed in front of the main broom 22 and extending transversely across the machine is a dirt bucket 26 which is adapted to receive the sweepings from the main broom 22 as the broom revolves in a counterclockwise direction. This dirt bucket is at least as wide as the main broom 22. The bucket 26 is supported on arms 27 which arc over the space occupied by the main broom 22 and are pivotally mounted on suitable brackets 29 secured to the rear axle 19.

In the operation of the machine, the arms 27 are swung up periodically to dump the con-

tents of the bucket 26 into a dirt box 28 which is disposed inside the sweeper housing.

For a more detailed description of the construction and operation of the dirt bucket 26, reference may be had to my copending application Serial No. 680,041 filed June 28, 1946.

According to the present invention an auxiliary side broom assembly 30 is mounted at one side of the operator's cab 12. The function of this side broom is to dig dirt out of the gutter and sweep it outwardly under the machine and against the dirt board 31. The dirt board 31 prevents the dirt from being thrown clear of the machine on the far side and directs it into the path of the oncoming main broom 22 which sweeps it up into the dirt bucket.

As shown in Figure 2 the housing for the mechanism for driving the side broom 30 comprises a main drive shaft housing 32, a gear housing 33, an upper side broom drive shaft housing 34 and a lower side broom drive shaft housing 35, all suitably connected by overlapping flanges and held together as by capscrews. The main drive shaft housing 32 comprises an elongated tube adapted at its inner end 36 to telescope over a cylindrical arm 37 which projects outwardly from the transmission housing 16a. An oil retainer ring 38 is positioned in a recess in end 36 around arm 37 to prevent escape of lubricating oil at this point. On the upper side of the housing 32 an opening is provided for a coupling lever assembly 39 the function of which will be described hereinafter. At its outer end a recess 32a is formed in the housing 32 to receive a ball bearing member 40. A flange 32b on the housing 32 is adapted to receive therearound the inner end of the housing 33 which is connected to the housing 32 by a plurality of capscrews 44.

In order to provide easy access to the mechanism at this end of the drive shaft, an opening 33a is provided in the upper surface of the gear housing 33 over which a removable plate 45 is secured by capscrews 46. An aperture 33b in the lower surface of the housing 33 communicates with an opening 47 in a main broom drive gear housing 48. The housing 48 is secured to the underside of the housing 33 by capscrews 49. A countershaft 50, journaled in the housing 48, is driven by means of a gear 51 keyed thereon and carries at its outer end a drive sprocket 52 by means of which the main sweeper broom 22 is rotated. To provide a bearing surface for the upper end 24a of the main broom support arm 24, a shoulder 48a has been formed in housing 48. The housing 48 is secured at its lower end through a pin 53 to a bracket 54 which is in turn secured to a structural member 13 by a plurality of bolts 55.

Near its central section housing 33 has an inwardly projecting ring 33c into which is fitted a ball bearing member 40a. A second opening in the lower surface of the housing 33 is adapted to receive therein an upwardly projecting annular flange 34a of the housing 34. Housing 34 is secured to the housing 33 by a plurality of capscrews 56.

The upper side of broom drive shaft housing 34 comprises an upper frusto-conical section 34b and a lower substantially semi-spherical section 34c connected by a cylindrical section 34d. An opening in the upper section 34b is adapted to receive a ball bearing member 57. Extending outwardly from the spherical surface of section 34c is an arm 34f which is secured to the gear housing 48 by capscrews 34g.

At the lower end of section 34c an inwardly disposed annular ring 34e provides a seat for a spherical-shaped upper member 35a of the housing 35 thus forming a ball joint. Positioned on a lower flange 35b of spherical-shaped member 35a (Figure 9) and secured thereto by capscrews 59 is a pair of curved clamps 58. At the upper end of clamps 58 a plunger 50 is urged against the outer surface of section 34c by a spring 61. Member 35a in conjunction with the clamps 58 provide a universally pivotal cap which permits the swinging of the housing to conform to the angular adjustments of the drive shaft without destroying its dirt-resisting seal. Any convenient number of clamps 58 suitably disposed on the flange 35b may be used. I have found that two clamps positioned substantially opposite each other to be a satisfactory arrangement. The clamps 58, bearing at their upper ends on the housing 34a provide a support means for member 35a and for a tubular guard member 62 which depends from the flange 35b by means of the capscrews 59. A lower tubular shaft shield 63 is adapted to telescope inside the shield 62. At its lower end the shaft shield 63 abuts an adapter plate 64 and is held thereon by a plurality of spring clips 65 which snap into a groove 63a on the inside surface of the shield 63. Clips 65 are fastened to an adapter plate 64 by capscrews 66.

As illustrated in Figure 2 the broom assembly 30 comprises downwardly extending bristles 70 which are secured in holes in a broom head 71 by taking double length bristles, bending them into U-shaped and forcing each end through adjacent holes in the broom head. The broom head 71 is secured to a broom top plate 72 by a plurality of bolts 71a.

For driving purposes the broom top plate 72 is secured to a flange 73a of a broom drive member 73 by means of the capscrews 74. A square central aperture 75 disposed parallel to the central axis of the broom 30 is provided in member 73. This aperture 75 is adapted to receive the square shank of a drive shaft 76. The use of a square drive shaft permits the broom to be driven by the shaft and still allows the broom to slide up and down relative to the shaft.

In order to permit angular adjustment of the broom, the drive shaft 76, which is centrally disposed in relation to the shaft shields 62 and 63, is keyed at 76a to one leg of a universal coupling 77 for rotation therewith. The shaft 76 is secured to the coupling by a nut 78. The other leg of coupling 77 is keyed at 77a to an upper drive shaft 80 for rotation therewith and is secured thereto by a nut 81.

To maintain its vertical alignment upper drive shaft 80, rotating inside the housing 34, is journaled in a sleeve 82 secured in section 34d. An oil seal 83 is disposed about the shaft 80 just below the sleeve 82. Near its upper end shaft 80 is also journaled in ball bearing member 57 positioned in a recess in the upper surface of the housing 34. Keyed to the upper shaft 80 for rotation therewith is a bevel gear 84 which is held against endwise movement by a locknut 85.

Rotation is imparted to bevel gear 84 due to it being in mesh with another bevel gear 86 which is keyed to a main drive shaft 87. The drive shaft 87 is journaled in a ball bearing member 40a which is held by ring 33c of the housing 33 and in a ball bearing member 40 which is held in a recess in the housing 32. Keyed to the shaft 87 at a point between the bearings 40 and 40a is a gear 88 which is adapted to drive the gear 51 and

thereby to drive the sprocket 52 as previously described. Spacer tubes 89 and 89a are disposed between the gear 88 and the bearings 40 and 40a. Movement of the shaft 87 toward the left is prevented by a locknut 90 threaded on the shaft 87 abutting the bearing 40.

At its inner end shaft 87 has a splined connection on which a coupling 91 is adapted to slide. A second spline shaft 92 protrudes outwardly from transmission housing 16a and is adapted to receive the tongue members 93 of coupling 91 (Figure 5) as the coupling is slid inwardly over the shaft 92. The sliding member 91a of coupling 91 is moved back and forth on the splined part 15 of the shaft 87 by means of a manually operated lever 39a of lever assembly 39.

In the position shown in Figure 2 the coupling has been slid into engagement with the spline shaft 92 thereby causing the shaft 87 to rotate 20 with shaft 92. If it is desired to disconnect these shafts, the lever 39a is swung about a vertical shaft 39b to which it is pinned. This will cause an end member 39c to be rotated through an arc due to the fact that it is secured to a vertical shaft 25 39b by a radius arm 39d. Member 39c projects downwardly into an annular groove 91b in the sliding member 91a. As the end member 39c is moved to the left in an arcuate path it causes the sliding member 91a to be moved to the left out 30 of engagement with the spline shaft 92. The vertical shaft 39b is disposed off center laterally in relation to the longitudinal axis of the shaft 87, as shown in Figure 5, in order that the arcuate path of the end member 39c will approximate 35 travel along the axis of the shaft 87 thus eliminating the possibility of being swung out of contact with the groove 91b of sliding member 91a.

Thus it is seen that the broom assembly 30 is mounted to be driven from the main transmission 40 of the sweeping machine by means of a bevel gear drive, having a sliding coupling member for disconnecting the drive and a universal joint for permitting the broom to be positioned at various angles.

When the side broom is not being used it is desirable that it be lifted out of contact with the street. In the present invention this is accomplished as illustrated in Figure 4, by means of a hydraulically operated cylinder 93 which is pivotally connected at one end to a bracket 94 attached to a frame member 13. At the other end hydraulic fluid is admitted to the cylinder at the inlet 93a. Adjacent the inlet 93a a piston rod 93b extends outwardly to be pivotally connected 50 through a pin 95 to a bellcrank 96. Said bellcrank 96 is pivoted by the pin 97 in a pair of hinge bars 98 which depend downwardly from a mounting tube 99 which is supported by frame members through the brackets 99a and 99b. A lift arm 100 is pivotally connected through a pin 101 to the bellcrank 96. The outer portion of the lift arm 100 is a rod 100a adapted for sliding engagement in a hanger eyebolt 102 which is pivotally threaded into a pivot housing 103. A lift yoke 104 has a stud 103a pivotally threaded into a threaded bore 103b in the housing 103 as seen in Figure 4.

As illustrated in Figure 3, the lift yoke 104 comprises a substantially U-shaped member 104a closed at its open side by a plate 104b which is secured thereto by the capscrews 104c. At opposite sides of the lift yoke 104 and on a line substantially at right angles to the axis of the lift arm 100, openings are provided in the lift yoke 104 for

two lift pins 105 which pivotally connect the lift yoke to a broom ring 106.

As best seen in Figure 2, the lift ring 106 comprises an upper member 106a which is secured to the adapter plate 64 by capscrews 68, thus being connected to the lower telescoping shaft shield 63. A lower member 106b of lifting ring 106 is secured to the upper member 106a by capscrews 107. Positioned between the upper and lower members of the ring 106 is the outer ring of a ball bearing member 108. The inner ring of the ball bearing member 108 is secured between a shoulder on the broom drive member 73 and a threaded retainer member 109. Thus it is seen that the broom 30 is free to rotate with the drive member 73 while the lift yoke 104 remains stationary. However, when the lift yoke is raised by the hydraulic cylinder, the broom assembly 30 will also be raised due to the lifting action transmitted through the bearing member 108 to the threaded retainer member 109.

In Figure 4 is illustrated in dotted lines a hydraulically operated broom lifting mechanism which is adapted to operate on a broom mounted on the outer side of the vehicle. In some cases as for instance on streets having one way traffic it is advantageous to have side brooms on either side of the vehicle in order that either gutter may be cleaned without running against the traffic.

A distinct feature of this invention is the ability of the hydraulic cylinder 93 to hold the broom in any position desired. For example this single acting cylinder will hold the broom entirely clear of the ground or it will hold it in sweeping position. As the bottom of the broom wears it is necessary that the broom be lowered and held in the new operating position. This is accomplished by means of the controls in the operator's cab, no mechanical adjustments being necessary.

It is also to be noted that side broom assembly 30 is rigidly secured to the sweeper machine proper at only two points, namely, at the lift yoke 104 and at pin 53 at the lower end of gear housing 48. The pin 53 is quickly removed by taking out the cotterpin and the yoke 104 is easily separated from the broom by unscrewing plate 104b from member 104a. Then by removing the chain from sprocket 52 and sliding upper end 24a of broom support arm 24 from its bearing 48a, the whole side broom assembly and drive may be removed as a unit. The end 36 of drive housing 32 will of course slide off the projecting arm 37 of transmission housing 16a. From the foregoing it is now clear that the whole unit may be assembled and aligned previous to installing it on the machine. Also, in organizations that use several machines, a spare broom and drive assembly can be kept on hand and quickly installed when repair or overhaul of the operating unit is required. Thus it would not be necessary to lay up an entire machine due to wear or breakage of any small part.

For best results in sweeping gutters it is desirable that only the outer front quadrant of the rotating broom contact the street. This permits a definite digging action that will dislodge caked mud in the gutter and at the same time will not impose an excessive frictional sweeping load on the drive mechanism. To secure this operating position it is necessary that the broom be pivoted about its universal joint in a direction toward the rear of the machine and in toward the machine proper.

This is accomplished (Figure 3) by means of two rods 110 and 111. Rod 110 is screwed into

the pivot housing 103 and locked therein by a jam nut 112. At its other end the rod 110 is pivotally suspended from the mounting tube 99 as best shown in Figures 6 and 7. Rod 110 projects through a pivot housing 113 which fits between the two legs of a forked member 114. A pivot pin 115 is threaded into each leg of the forked member 114 and has an unthreaded end 115a extending into the pivot housing 113 being journaled therein. Thus the rod 110 by means of its position in the pivot housing 113 is free to pivot in relation to the forked member 114.

Referring to Figure 7, the forked member 114 is hung from the mounting tube 99 by means of an upper rod 114a which extends upwardly through a sleeve 116 which has been welded in place in a vertical opening which has been cut in the tube 99. A washer 117 is seated on the upper end of the sleeve 116 and a slotted head nut 118 is screwed down on a threaded portion of the upper rod 114a. The rod 114a is prevented from unscrewing by a cotterkey 119 inserted through the rod and confined in the slotted head nut 118.

25 A coil spring 120 is disposed about the rod 110 abutting at one end on the jam nut 112 and at the other end on the pivot housing 113. This spring 120 tends at all times to urge the broom assembly away from the machine. On the end of 30 the rod 110 adjacent the pivot housing 113 a nut 121 and a jam nut 122 are disposed for adjusting the rod in relation to the housing 113.

The rod 111 is pivotally connected to the pivot housing 103 by means of a pin 123 (Figure 8) 35 which projects through a pivot member 124 to which the rod 111 is secured as by welding. At the other end rod 111 is suspended from the mounting rod 99 in the same manner as was described in connection with the support of the 40 rod 110. Also, to urge the broom away from the machine a spring 125 is provided and a nut 126 and a jam nut 127 is furnished for adjusting the rod 111.

It is readily seen from Figure 3 that the broom 45 may be adjusted in a direction toward or away from the machine by shortening or lengthening the effective length of the rods 110 and 111 through manipulation of the nuts at the end of the rods.

50 Also, it will be noted that if one rod is shortened more than the other the broom will be moved toward the front or the rear of the machine as the case may be. For example, if the rod 111 is lengthened and the rod 110 is shortened, the broom 55 assembly will move forward. To obtain this result pivoting must take place about the pin 123. It is also to be noted that in all adjustments of the broom, the rod portion 100a of the lift arm 100 is free to slide in or out in the eyebolt 102 and also that the eyebolt 102 is free to pivot in its 60 screw fitting in the pivot housing 103.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

70 1. In a sweeping machine including a side broom, means for adjusting the operating position of said side broom comprising a rigid V-shaped member pivotally secured at its outer ends to the frame of said sweeping machine and 75 at its apex to said side broom, and means for

adjusting the distance between the outer pivotal connection of each arm of said V-shaped member and the apex thereof.

2. In a sweeping machine including a side broom, means for adjusting the position of the side broom comprising a pivot member secured to said broom, a first arm rigidly secured at one end to said pivot member and pivotally connected at the other end to the frame of said sweeping machine, a second arm pivotally connected at one end to said pivot member and at the other end to the frame member of said sweeping machine, a spring member disposed on each of said arms between said pivot member and said frame, and means operative on each of said arms for adjusting the length of each of said arms between said pivot member and said frame independent of the other arm.

3. A street sweeping machine including a power driven broom pivotally mounted in a universal socket, means for adjusting the universally pivoted position of the broom comprising a V-shaped member pivotally attached at its outer end to the frame of the machine and having its apex pivotally secured to said broom, and spring urged means for adjusting the length of each of said arms between the apex and the outer pivotal connection.

4. In combination in a street sweeping machine, a side broom mounted for universal pivoting movement and means for simultaneously adjusting said side broom both laterally and longitudinally of the machine, said means comprising a pivot member secured to said broom and pivotally connected at the other end to the frame of said sweeping machine, a second arm pivotally connected at one end to said pivot member and at the other end to the frame of said sweeping machine and a spring disposed on each of said

arms between said pivot member and the frame.

5. In a street sweeping machine, a drive shaft, a universal joint in said shaft, a side broom assembly mounted on said drive shaft for pivotal movement therewith about said universal joint, and spring urged members connected to said broom assembly and connected to the machine at longitudinally spaced points thereon to provide thrust components acting in opposite longitudinal directions as well as transversely of the machine.
